APPARATUS FOR CONDITIONING SHOE STIFFENER PARTS AND THE LIKE

Stanley P. Lovell, Newton, Mass., assignor to
Arden Box Toe Company, Watertown, Mass.,
a Corporation of Massachusetts

Application January 13, 1932. Serial No. 586,299

2 Claims. (Cl. 91—46)

This invention relates to an apparatus for conditioning shoe stiffener parts for assembly with shoe uppers.

There are now on the market shoe stiffener parts, such as box toe blanks, which are normally in a stiff condition but which can be softened to a limp and mouldable condition just before they are assembled with the shoe upper and the assembly is subjected to the pulling-over and lasting operations. The conditioning of the box toe blanks is often performed at the shoe factory by dipping them into solvents or gelatinizing liquids for the stiffening agent present in the blanks. Thus, the blanks may be made up of a suitable fabric stiffened by nitrocellulose, cellulose acetate, or other stiffening medium soluble or gelatinizable in organic liquids, which function to reduce the stiff blanks to the desired limp and mouldable condition after a suitable period of contact therewith, and which are volatilized at room temperature, thereby causing a setting or hardening of the blanks in place in the shoe.

The apparatus of the present invention is designed to handle one or more rows of spaced blanks and it permits one row of the blanks to be lowered into a bath of the liquid and then removed from the bath so as to drain and to acquire the desired mouldable condition without a superfluity of liquid therein. Each row of blanks is supported in a carriage provided with means for resiliently holding the blanks in vertical relationship, preferably with substantially all their surfaces exposed to contact by the liquid. Each carriage is mounted on mechanism permitting its lowering into the bath and then automatically causing its return to the normal position above the bath. The carriages are arranged side by side, so that a single bath can serve for all of them, the row of blanks supported in one of the carriage being usable by the operator while the remaining row or rows are being drained of excess liquid and acquiring the proper softness for use.

With the foregoing and other features and objects in view, my invention will now be described in conjunction with the accompanying drawings, wherein

Figure 1 shows an apparatus embodying the present invention and comprising two carriages for blanks maintained in separate compartments, one of these compartments being illustrated in vertical, transverse section, and the other in front elevation.

Figure 2 is a horizontal section through the apparatus on the line 2—2 of Figure 1.

Figure 3 shows a plan view of the apparatus.

Figure 4 constitutes a vertical, longitudinal section of the apparatus on the line 4—4 of Figure 1 and illustrates the carriage in its normal position above the bath and in its submersed position.

Figure 5 depicts in perspective one of the carriages disassociated from other parts.

Figure 6 is a sectional detail along the line 6—6 of Figure 4.

Figure 7 shows in perspective a carriage provided with means for wiping as well as for resiliently holding the blanks.

Figure 8 represents a fragmentary section on the line 8—8 of Figure 7, and illustrates the manner in which a blank is held.

Figure 9 is a view similar to Figure 7 but showing a carriage with another form of wiping and blank-holding means.

Figure 10 is a fragmentary section on the line 10—10 of Figure 9 and illustrates the way in which a blank is held.

Figure 11 represents a fragmentary section on the line 11—11 of Figure 10.

Referring in detail first to Figures 1, 2, and 3, the apparatus as a whole can be considered as being made up of a main vat or container 1 of rectangular shape and a pair of carriages and associated parts 2 arranged in side by side relationship in the vat. In back of the vat 1, there is a closed supply tank 3, which feeds the liquid through a spout 4 discharging below the surface of a liquid pool kept in a lower reservoir 5 whose bottom is shown disposed somewhat above the bottom of the vat 1. The liquid flows from the reservoir 5 through openings 6 formed in the rear wall of the vat and forms a main pool of liquid in the vat. As liquid in the main pool is removed through absorption by the blanks, fresh liquid enters therewith from the reservoir 5, since the level of liquid in the main pool is always determined by the level of liquid pool in the reservoir 5, which latter level is automatically kept constant by a flow of fresh liquid from the barometric liquid head in the supply tank 3. The supply tank 3 is removably supported on the rear and side walls of the reservoir 5, and so can be refilled when necessary by the operator, to ensure a feed to the reservoir.

The top of each carriage 2 is constructed essentially as a grating having transverse slots 60 therein permitting the insertion of box toe blanks therethrough. The slots are shown defined by 110

spaced bars 7 of generally triangular cross-section, whose bases constitute the under-faces of the bars and whose sides thus diverge upwardly, as seen best in Figures 4 and 5. These bars, 5 which can be formed as light, hollow elements from suitable sheet metal, may be fixed to side partitions 8 mounted on raising and lowering mechanism presently to be described. Each bar has suspended therefrom one or more pairs of 10 outwardly bowed or convex leaf springs 9, which can be made as a single strip of resiliently flexible metal having a horizontal upper portion 10 anchored as by a rivet 11 to the base of the bar. A spring of one bar is in pressing contact at its 15 center with a spring of an adjacent bar, so as to form resilient holding or gripping means for a box toe blank. All the operator has to do is to grasp a rigid box toe blank between his forefinger and thumb and to insert it downwardly 20 through the slot, so as to separate the contacting springs, and thus when released to ensure retention of the blank in a vertical position. The space between the apices of the bars is sufficient 25 to accommodate easily the forefinger and thumb of the operator, so that he may have no difficulty in placing the blank in the carriage, with its upper edge somewhat below the apices. After a 30 row of blanks has been placed in the carriage, it is lowered until it is completely submerged in the liquid bath in the tank 1.

Each carriage is mounted on mechanism permitting its lowering into the bath to the dotted line position shown in Figure 4, and then automatically causing its return to the normal position shown in full lines above the bath. To this end, the side partitions 8 include between them near their lower edges a housing or box 12 for a horizontal shaft 13 passing through a pair of bearings 14 fixed in place to the walls of the box 35 near the partitions 8. Immediately outside of each partition 8, a gear 15 is affixed to the shaft and is in engagement with a vertical rack 16 fixed to a supporting member 17, which has a vertical slot therein serving to receive a key 18 40 formed as a cylindrical element of reduced cross-section at the end of the shaft. The shaft is thus free to rotate and to translate vertically, but it is restrained from other movement. The possible 45 rotary and translatory movement of the shaft imparting the desired up-and-down movement of the carriage is inhibited by a coil spring 19 convoluted about the shaft, one end of the spring being anchored to the shaft, and the other to the box 12 under sufficient tension to keep the carriage 50 in its normally elevated position above the bath. When the carriage is caused to descend under an applied force, so as to rotate the shaft and further tension the spring, the removal of the force is attended by an automatic ascent of the carriage to its normally elevated position under spring action. Each carriage is shown provided 55 with an upstanding push handle 200, whose lower end portion may be secured to a partition 8 and whose handle portion may project sufficiently 60 above the vat 1 so that it is still outside the vat when the carriage has been forced to its lowermost position in the vat.

The carriages and other associated parts thus far described are designed to be readily disassembled from the vat when cleaning of the vat is in order. Accordingly, a suitable framework for this purpose has been shown, consisting mainly of a rectangular box 20 for each of the two carriages. Both boxes can be made to fit nicely into 65 the vat, in the side-by-side relationship best

shown in Figure 2, to constitute essentially two separate compartments. Each box can be fabricated of suitable sheet metal and include reinforcing posts 21 at its corners, and inwardly turned flanges 22 at the upper and lower edges 80 of its walls. The supporting members 17 for each carriage are secured to opposite walls of a box, wherefore, by lifting a carriage by the handle 200, it can be removed together with the corresponding box from the vat. Preferably, as best 85 shown in Figures 1 and 4, the flanges 22 at the upper edges of the box engage over the top of the carriage and serve to stay the ascent of the carriage, which ensues rapidly under spring action. This means that the carriage strikes 90 against the flanges and excess liquid is shed from the blanks as a result of the impact. A suitable slot can be formed through one of the upper flanges 22 to allow the vertical movement of the handle 200 therethrough.

As already indicated, the box toe blanks for which the apparatus of the present invention serves usually require the use of a volatile solvent. Consequently, an atmosphere of the fumes of the volatile solvent tends to accumulate above the 100 pool of liquid solvent in the vat 1. This atmosphere is conducive to the softening and conditioning of the blanks, and it is desirable that as little fumes as possible be lost on account of diffusion into the air. This desideratum is attained by 105 simply closing that compartment in which the blanks are undergoing conditioning while the other compartment is open to permit the removal of conditioned blanks therefrom. The closure for this purpose can conveniently take the form 110 of a single angular member composed of two covers 24 arranged at right angles to each other and secured at their region of convergence to a rock-shaft 25 journaled in a pair of brackets 26, which can be anchored as by screws 27 to the upper 115 adjacent flanges 22 of the two boxes. The boxes are thus tied together so that they can be lifted as a single unit from the vat by the operator, who can conveniently effect such lifting by grasping the handles 200. The two covers are 120 shown provided with a brace and handle piece 28 bridging the angular gap between the covers. They may be made of sheet metal and turned downwardly at their margin portions 29, which 125 can rest on the upper flanges 22. The cover can readily be rocked or tilted to open one compartment containing conditioned blanks and to close the compartment containing fresh blanks which the operator has just put through immersion.

The box toe blanks now on the market are 130 usually skived at their marginal areas, as this avoids discomforting the foot on account of abrupts inside the shoe as well as raising unsightly ridges in the shoe upper. The box toe blanks 30 shown in Figure 1 of the drawings are 135 therefore of this type and have the usual skived marginal portions 31. They are preferably placed in the carriage by the operator, with their tip edges at the highest point and their vamp edges at the lowest point. In consequence of this disposition of the blanks, the excess liquid absorbed thereby during immersion in the liquid bath gravitates toward the vamp edges and thence drips into the bath, thereby ensuring the highest state of gelatinization where it is most desired, namely, 145 at the zone of the vamp edges. Indeed, in the case of blanks wherein cellulose derivatives like nitro-cellulose and cellulose acetate serve as the stiffening medium, the gelatinization may be so pronounced near the vamp edges that there is 150

some exudation of the gelatinized derivative at this locality. The exuded gelatinized derivative serves to bond the blank together with the lining and the shoe upper between which the blank is inserted. Such bonding is of value, in that it does away with a loose lining and at the same reinforces the forepart of the shoe. The tip areas of the blanks are the "driest," in the sense that they contain no superfluity of gelatinized cellulose. 10 This enables the operator to grasp this area of the blank without smudging of the finger tips and hence without danger of soiling the shoe upper. The so-called "lasting allowance" at the tip areas of the blanks also lends itself to easy removal in 15 what is known as the bed-lasting operation, as it is not unduly flabby on account of the presence of excess gelatinizing liquid.

There are some types of blanks which are so absorptive that notwithstanding shaking and 20 draining after immersion, they still contain more liquid than is desired at the time of assembly with the shoe uppers. In such case, the carriage is preferably provided with means not only for resiliently engaging and holding the blanks in place 25 vertically but for wiping them as they are removed from the carriage for use. A carriage so constructed is shown in Figure 7, wherein the carriage top is illustrated as taking the form of a grating having plane-faced bars 32 defining slots 33 through each of which a blank can be passed. 30 A resiliently flexible strip 34, for instance one made of rubber, may be suitably affixed at an edge of each bar 32 so as to project toward the strip of an adjacent bar, with the outer edges 35 of the strips substantially contacting. When a rigid or unsoftened blank 36 is passed downwardly through a slot 33, the strips 34 are flexed downwardly at their outer edges and are caused to engage and hold the blank in place, as best shown in 40 Figure 8. Upon the removal of the blank after its submersion in the liquid, excess liquid is wiped from its surfaces and/or squeezed from its interior by the strips.

In lieu of rubber strips, the means shown in 45 Figures 9, 10 and 11 might be used for the same purpose. As shown therein, a helical spring 37 fixed as at its ends to the carriage partitions 3 may be arranged immediately under an edge of 50 each bar so that its turns or convolutions cooperate with those of an adjacent spring to engage and resiliently hold a blank 36 passed downwardly through a slot 33, as best shown in Figure 10. The turns or convolutions of the springs may be crowded together or closely spaced, as best shown 55 in Figure 11, wherefore they can act to wipe substantially all of the surfaces of the blank which contact therewith as the blank is being withdrawn. This wiping and/or squeezing action of the springs on the blank serves the purpose of 60 removing such superfluous liquid as may be present on the faces and in the interior of the blank.

It is thus seen that my apparatus is of a simple, compact construction, completely devoid of pow-

er-actuated parts which might give off sparks and thus cause the firing or exploding of the volatile and highly combustible liquids used for treating the blanks. The top of the carriage, with its grating of bars, ensures a positive restoration of liquid entrained thereby to the pool; and the shock of the carriage coming to rest, as well as the subsequent draining period allotted to the blanks, are consonant with a perfect conditioning of some types of blanks for assembly with the shoe upper. While it is possible to provide the carriage with an air chamber or other float to return it automatically to its normally elevated position above the bath, nevertheless I prefer the more sudden recoil of the carriage afforded as by the spring mechanism described. If the blanks are of a highly absorptive character and need wiping as well as draining after immersion in the liquid, the carriages may include the wiping means shown in Figures 7 to 11 inclusive or other suitable means for wiping or pressing excess liquid from the blanks. The blanks are presented to the operator in such a position as to be removed and handled with minimum lost motion, as they are best grasped by their tip portions for placement between the shoe upper and lining. Because they are kept above the bath in an atmosphere charged with vapors arising from the bath, they can be maintained in the desired soft and mouldable condition indefinitely.

I claim:

1. In apparatus of the class described, a carriage for receiving a row of blanks in spaced, vertical relationship, a horizontal shaft on which said carriage is mounted rotatably secured to said carriage, a gear affixed to said shaft, a vertical rack with which said gear engages, means permitting a downward movement of said carriage under an applied force so as to cause a rotation of said shaft by said rack, and a coil spring 110 encompassing said shaft and one end of which is fixed to said shaft and the other to said carriage, whereby said spring becomes tensioned during the descent of said carriage and causes its automatic ascent when the applied force is removed.

2. In apparatus of the class described, mechanism including a carriage for receiving a row of blanks in spaced, vertical relationship, a horizontal shaft on which said carriage is mounted rotatably secured to said carriage, a gear affixed at 115 each end of said shaft, a vertical rack with which said gear engages and forming part of a supporting framework for said carriage, said framework further including means for permitting vertical translation of said shaft and up-and-down movement of said carriage mounted thereon, and a coil spring encompassing said shaft and one end of which is fixed to said shaft and the other to said carriage, whereby said spring becomes tensioned during the descent of said carriage, said mechanism being capable of assembly as a unit with 120 a vat of liquid for softening said blanks.

STANLEY P. LOVELL.
